UNITED STATES PATENT OFFICE.

LLOYD BOWMAN, OF DETROIT, MICHIGAN, ASSIGNOR OF ONE-HALF TO WILLIAM E. EASTMAN, OF DETROIT, MICHIGAN.

CONCEALED HINGE.

1,152,000.

Specification of Letters Patent. Patented Aug. 31, 1915.

Application filed November 20, 1914. Serial No. 873,083.

To all whom it may concern:

Be it known that I, LLOYD BOWMAN, citizen of the United States, residing at Detroit, county of Wayne, State of Michigan, 5 have invented a certain new and useful Improvement in Concealed Hinges, and declare the following to be a full, clear, and exact description of the same, such as will enable others skilled in the art to which it 10 pertains to make and use the same, reference being had to the accompanying drawings, which form a part of this specification.

My invention relates to an improvement in concealed hinges and is particularly 15 designed for use on automobile bodies.

The object of my invention is to provide 20 a device adapted to be concealed in the frame and the door of an automobile body and which is relatively strong, simple in construction and inexpensive to manufacture.

A further object of the invention is to 25 provide suitable means adapted to restrict the opening of the hinge, whereby the door cannot be carelessly thrown back in contact 30 with the body of the vehicle to mar its finish,—the construction being such that the coacting leaf members of the hinge while free to open within prescribed limits contact with each other to limit the opening of the door.

Other advantages and improvements will 35 hereafter appear.

In the drawings accompanying this specification: Figure 1, is a perspective view of the hinge opened. Fig. 2, is a perspective view of one leaf member of the hinge. Fig. 3, is a perspective view of the other leaf member of the hinge. Fig. 4, is a horizontal 40 sectional view through the hinge and a fragmentary portion of the door and its casing, showing the door closed. Fig. 5, is a similar horizontal sectional view (taken on line 5—5 of Fig. 1) showing the door open.

Referring now to the letters of reference placed upon the drawings: A, denotes one leaf of the hinge pierced by a pintle C. B, a co-acting leaf member provided with a substantially arc-shaped tongue B' integral therewith and partially formed by cutting the body of the leaf B as indicated at b.

b' is an eye on the end of the tongue B' to receive the hinge pintle, connecting the

respective members of the hinge together. 55 The member A, is also partially cutaway at a to provide an opening through which the tongue B' of the coacting leaf member may pass, leaving a cross bar a' between the cutaway portion and the hinge pivot to serve 60 as an abutment for the flattened portion b², of the tongue, whereby the degree of opening of the hinge may be limited.

D, denotes a recess formed in the door casing to receive the tongue B', when the 65 door is closed.

It will be apparent that as the leaf members of the hinge are lodged respectively in the opposing recessed portions of the door and casing, the hinge will be concealed from 70 view when the door is closed and that upon opening the door the flattened portion b², of the tongue B' will contact with the bar a' of the coacting leaf member, to limit the degree of opening of the door and thereby 75 preventing it from being carelessly thrown back into contact with the body of the vehicle whereby the finish may be marred.

Having thus described my invention what I claim is:—

A hinge of the type described, including 80 pintle articulated leaves, one leaf having a central quadrant-like tongue, with its free end terminating in an eye, said tongue being of right-lined formation for a portion 85 thereof intermediate said eye and its curvature, and the other leaf having in its outer longitudinal edge a central recess arranged to receive, and provide for the movement therethrough of said tongue, said leaf also 90 having intermediate its pintle-receiving eyes, a second recess arranged to receive the eye of said tongue for the alinement of said eye with the aforesaid eyes and the reception of the pintle, the curved or quadrant- 95 like portion of said tongue spanning the resultant reentrant angle between the leaves, at points inwardly from the outer longitudinal or vertical edges of said leaves, to allow of the leaves taking a relatively parallel and right-angled position, respectively.

In testimony whereof, I sign this specification in the presence of two witnesses.

LLOYD BOWMAN.
